(57) CLAIM

The ornamental design for a pocket tie, as shown and described.

DESCRIPTION

FIG. 1 is a front view of a pocket tie, showing the new design in its environment;

FIG. 2 is a front elevation view of the pocket tie, shown without environment;

FIG. 3 is a left-side elevation view thereof;

FIG. 4 is a right-side elevation view thereof.;

FIG. 5 is a rear elevation view thereof;

FIG. 6 is a top plan view thereof; and,

FIG. 7 is a bottom view thereof.

The broken lines shown on the surface of the article in FIGS. 1, 2 and 5 depict portions of the pocket tie that form no part of the claimed design. The broken lines showing the person in FIG. 1 depict environment and form no part of the claimed design.

1 Claim, 3 Drawing Sheets
